US00D888226S

(12) **United States Design Patent** (10) Patent No.: **US D888,226 S**
van Roosmalen et al. (45) Date of Patent: ** Jun. 23, 2020

(54) **FLUID INJECTOR**

(71) Applicant: **BAYER HEALTHCARE LLC**, Whippany, NJ (US)

(72) Inventors: **Linda van Roosmalen**, Gibsonia, PA (US); **Gerald Callan**, Cranberry Township, PA (US); **Daniel Moore**, Pittsburgh, PA (US); **Kent Diasabeygunawardena**, Nashua, NH (US); **Daniel Van Alphen**, Lexington, MA (US); **Engin Hassamanci**, Medford, MA (US)

(73) Assignee: **Bayer Healthcare LLC**, Whippany, NJ (US)

(**) Term: **15 Years**

(21) Appl. No.: **29/680,381**

(22) Filed: **Feb. 15, 2019**

(57) **CLAIM**

The ornamental design for a fluid injector, as shown and described.

DESCRIPTION

FIG. 1 is a top perspective view of a fluid injector showing our new design in accordance with a first embodiment; FIG. 2 is a front elevation view thereof with a support bracket in a retracted position;

FIG. 3 is a front elevation view thereof with a support bracket in an extended position;

FIG. 4 is a rear elevation view thereof;

FIG. 5 is a right side elevation view thereof;

FIG. 6 is a left side elevation view thereof;

FIG. 7 is a top view thereof;

FIG. 8 is a bottom view thereof;

FIG. 9 is a top perspective view of a fluid injector showing our new design in accordance with a second embodiment;

FIG. 10 is a front elevation view thereof with a support bracket in a retracted position;

FIG. 11 is a front elevation view thereof with a support bracket in an extended position;

FIG. 12 is a rear elevation view thereof;

FIG. 13 is a right side elevation view thereof;

FIG. 14 is a left side elevation view thereof;

FIG. 15 is a top view thereof; and,

FIG. 16 is a bottom view thereof.

The portions of the fluid injector shown in broken lines form no part of the claimed design.

1 Claim, 16 Drawing Sheets
